Attorney

UNITED STATES PATENT OFFICE.

NATHAN S. MEYER, OF NEW YORK, N. Y.

PACKAGE.

Application filed March 13, 1926. Serial No. 94,611.

My said invention relates to a package intended primarily for use in transportation of buttons, the appearance of which is easily marred, such as military and other embossed or highly polished buttons, and it is an object of the same to provide a package of this character affording ready means of display of the contents but protecting them from all contact with extraneous objects while in process of transportation or in storage.

Referring to the accompanying drawings which are made a part hereof and on which similar reference characters indicate similar parts,

15 Fig. 1 is a perspective of my device in open position, and

Fig. 2, a transverse section of the same in closed position.

In the drawings reference character 10 indicates a flat portion of a sheet of cardboard or similar material which is so folded that the part 10 forms the bottom of a container for buttons. This container has side portions 11 and 12, and a top 13 with a flap 14 formed integrally with and connected directly to the side 11, said flap having a tongue portion 15 engageable in a slit in the bottom at 16 to hold the package securely closed. The bottom has integral laterally projecting portions 17 and 18 forming the ends of the device with creases providing tabs 19 and 20 which fold under the top 13 when the container is closed.

A shelf portion 21 is connected by means of an intermediate spacer strip 11' with the bottom 10 and this shelf as here shown is co-extensive with the bottom 10 and the top 13, all parts of the container being stamped or cut out of a single piece of cardboard and creased at appropriate places for convenient folding. The shelf is provided with slots 22 of conventional form for receiving the shanks of buttons 23 which are held in place by clips 24.

It will be seen from the foregoing description that my device makes a package which

will securely protect military and other ornamental buttons until ready for use and at the same time a package that can readily be opened for inspection or left approximately in the position of Fig. 1 for display, after which it can readily be closed again preparatory to further transportation or storage.

The tongue portion 15 may be set to rest on the bottom portion near the crease joining the bottom 10 and spacer. The shelf portion 21 may then be leaned back to rest against the outer side of the flap and the edge of the top 13. When in this position the shelf provides an attractive display for the buttons or other articles which are attached thereto.

It will be obvious to those skilled in the art that various changes may be made in my device without departing from the spirit of the invention and therefore I do not limit myself to what is shown in the drawings and described in the specification but only as indicated in the appended claim.

Having thus fully described my said invention, what I claim as new and desire to secure by Letters Patent, is:

A container and display box for buttons comprising a strip of card board or the like foldable to form a closed box-like container having integral top, bottom, side and end walls with an integral spacer strip and a perforated button supporting shelf held by said strip between the top and bottom of the container, the bottom being slotted and the top having a flap adapted to be folded under the bottom with a tongue engaging in said slot, the shelf being adapted also to rest against the flap when in open position and to be inclined rearwardly to serve as a display device for the buttons, substantially as set forth.

In witness whereof, I have hereunto set my hand at New York, New York, this 4th day of March, A. D. nineteen hundred and twenty-six.

NATHAN S. MEYER.
